(57) **CLAIM**

I claim, the ornamental design for the bell and diaphragm disposable cover, as shown and described.

DESCRIPTION

FIG. 1 is a front elevational view of the bell and diaphragm disposable cover showing my new design;

FIG. 2 is a top plan view of the bell and diaphragm disposable cover thereof;

FIG. 3 is a bottom plan view of the bell and diaphragm disposable cover thereof; and,

FIG. 4 is a perspective view of the bell and diaphragm disposable cover thereof.

The broken line showing of the stethoscope is included for the purpose of illustrating environment and forms no part of the claimed design.
